ABSTRACT: This invention relates to a unique compact having means to maintain a makeup applicator separated from the makeup. This compact comprises a base, a cover, a pressed powder cake, an applicator and a separator element. The separator element comprises two plastic discs joined by a plastic hinge, one of the discs being secured to the interior of the compact base. The remaining disc is free to pivot to a position covering the makeup, thereby protecting the makeup from contamination.

COMPACT DISC

It is desirable in the use of a compact using the conventional pressed powder makeup cake to keep the applicator (powder puff) from being stored in permanent contact with the makeup. Otherwise, the applicator may transfer oils and makeup from the face to the surface of the powder cake causing soiling, glazing, hardening or discoloration of the makeup. A cellophane disc is commonly supplied when a compact is purchased for purpose of separating the applicator from the makeup. However, this separator is unattached and is normally thrown after first use.

The object of this invention is to provide a compact having a permanently attached separator disc which may be conveniently used and manufactured.

Other advantages of this invention will become apparent from the more detailed description which follows. The accompanying drawings include:

FIG. 1 is an assembled perspective view of the compact including the separator disc;

FIG. 2 is an exploded perspective view of all the elements of the compact; and

FIG. 3 is a plan view of the separator element.

Referring specifically to the drawings, this invention comprises a compact having a base 1, a cover 2, a pressed powder cake makeup element 3 and a separator element 4.

The separator element 4 of the preferred embodiment is constructed of plastic and cut or stamped out of a single sheet. The element 4 is made up of an anchor disc 5 and separator disc 6 which are joined by a hinge 7. The anchor disc 5 is secured to the interior of the base 1 after which the pressed

powder cake 3 is put in its place over the anchor disc 5 in base 1. It can readily be observed that the separator disc 6 can now be pivoted over the powder cake 3 to its protective position. The powder puff 8 would be placed on top of the separator disc 6 and is thereby kept separated from the makeup. To use the makeup, the separator disc is merely pivoted conveniently away from the powder cake. After the application of the makeup powder, the separator disc is returned to the original protective position on top of the powder cake.

10 This simple design provides a convenient permanently attached separator which may be manufactured efficiently and simply in large numbers. The separator element may be variety of shapes, sizes and materials.

I claim:

- 15 1. A compact for containing makeup comprising:
A. a base unit forming a container for the makeup;
B. a cover forming a closure for the base;
C. a pressed powder makeup cake inserted in the base;
D. a separator element comprising an anchored member
and a separator member joined by a hinge, the anchored
member is secured to the interior of the base under the
makeup cake, the separator member being free to pivot
on its hinge to cover the top of the makeup cake said
anchor member, separator member and hinge being
formed in one piece from a single sheet of flexible materi-
al; and
- 20 E. and applicator which is placed over the separator
member when said separator member is in its normal
makeup-covering position.
